(57) **CLAIM**

The ornamental design for a plug holder for a charging station, as shown and described.

DESCRIPTION

FIG. 1 is a perspective view of a plug holder for a charging station;

FIG. 2 is a perspective view of the plug holder for a charging station of FIG. 1 showing an attached card reader as part of the environment;

FIG. 3 is a front view of the plug holder for a charging station of FIG. 1;

FIG. 4 is a rear view of the plug holder for a charging station of FIG. 1;

FIG. 5 is a left-side view of the plug holder for a charging station of FIG. 1;

FIG. 6 is a right-side view of the plug holder for a charging station of FIG. 1;

FIG. 7 is a top view of the plug holder for a charging station of FIG. 1;

FIG. 8 is a bottom view of the plug holder for a charging station of FIG. 1;

FIG. 9 is a rear perspective view of the plug holder for a charging station of FIG. 1; and,

FIG. 10 is a cross-sectional view taken along the lines 1-1 of the plug holder for a charging station of FIG. 3.

The broken lines depict portions of the article that form no part of the claimed design.

1 Claim, 7 Drawing Sheets
